UNITED STATES PATENT OFFICE.

LEWIS M. RUMSEY, OF ST. LOUIS, MISSOURI.

DRIVE-CHAIN.

SPECIFICATION forming part of Letters Patent No. 252,005, dated January 3, 1882.

Application filed December 7, 1881. (No model.)

To all whom it may concern:

Be it known that I, LEWIS M. RUMSEY, a citizen of the United States, residing at St. Louis, in the county of St. Louis and State of Missouri, have invented certain new and useful Improvements in Drive-Chains, of which the following specification, taken in connection with the accompanying drawings, is a full, clear, and exact description, which will enable any person skilled in the art to construct and use the same.

My invention relates to that form of chains which are made up of wire links, and are adapted to be coupled and uncoupled by means of the elasticity of the wire—such, for example, as shown in patent granted to me August 3, 1880, No. 230,662; and it consists in certain details of construction, which I will now proceed to describe.

Referring to the drawings, in which like letters of reference mark similar parts, Figure 1 is a perspective view of two links coupled together. Fig. 2 is a longitudinal central section; and Fig. 3 is a perspective view of a single link slightly modified.

Each link consists preferably of a simple piece of wire with two eyes, C C, formed on the free ends thereof, and when bent as hereinafter described having end bar, B, and two hooks D D.

In the construction of the links I prefer to use square wire, although I sometimes use round or oval; but the square form gives broader bearing-surfaces for the articulations, when the links are coupled together, and is better on this account.

As before stated, the link has but one cross-bar, B, which is at some distance from one end, as the two hooks D D project beyond it. This bar as well as the two hooks and the side bars are all in the same plane; but the eyes C C on the free ends of the side bars are formed at right angles, or nearly so, to the general plane of the link. At the point where the hooks are formed the wire is doubled, which adds both to the strength of the link and increases the bearing-surface.

In Fig. 1 the cross-bar is shown as straight, or bent at a right angle to the side bars; but in Fig. 3 I have shown a slightly modified form, where the end bar is curved outwardly. For some purposes this form may be preferable, as the links are less easily disengaged.

The parts may also be reversed, and still be within the scope of my invention—that is to

say, the hooks may be formed on the free ends of the wire and the eyes on the doubled or bent end, it only being necessary to the successful operation of forming the links into chains that the hooks and eyes should be at 60 right angles to each other.

In the formation of the links the wire is cut into suitable lengths proportionate to the sized link required, the eyes are formed on the ends, and it is bent twice at right angles. The blank 65 has then the form of a three-sided parallelogram, and the hooks are formed at the bends or corners, which completes the link. The whole operation may be performed on a suitable wire-bending machine, or with a drop- 70 press.

The mode of coupling and uncoupling the links will be apparent. The links being made of spring metal, it is only necessary to press the side bars of a link toward each other until they will engage with the hooks on the end of an adjacent link, when the elasticity of the metal will prevent their accidental separation. Any number of links may be thus coupled until a chain of the desired length is formed. 75

Having thus fully described my invention, what I claim as new is—

1. A link for drive-chains formed of spring metal, with two parallel or nearly parallel side bars, having eyes at one end and hooks at the 85 other, said hooks and eyes being at right angles to each other, and the side bars being connected by a cross bar at one end only, substantially as specified.

2. A link for drive-chains formed of spring 90 metal, with two parallel or nearly parallel side bars, having at one end eyes or loops formed thereon and at right angles thereto, and at the opposite end a cross-bar, and inwardly-bent projecting hooks in the same horizontal plane 95 as the side and cross bars, and adapted to be coupled to similar links to form a chain, substantially as set forth.

3. A link for drive-chains formed of spring metal, square or rectangular in cross-section, 100 having two side bars with eyes formed on the free ends thereof, and connected at the opposite end by a cross-bar, and provided with doubled projecting hooks, said hooks being in the same horizontal plane as the side and end 105 bars, and the eyes at right angles thereto, substantially as set forth.
